SETTING HEAD FOR MACHINES FOR THE
GRINDING OF WORMSGabriel Lechesne, Montreuil-sous-Bois, France,
assignor to Paul Durand, Neuilly-sur-Seine,
Seine, France

Application March 16, 1935, Serial No. 11,485

4 Claims. (Cl. 125—11)

The present invention relates to worm gear grinding machines wherein an abrasive wheel is employed and more particularly to an attachment or setting head for such machines wherein the 5 grinding or cutting surfaces of the abrasive wheel may be reset or kept in proper form for grinding the gears while the machines are in operation.

Among the principal objects of the invention 10 is the provision of an attachment for worm gear grinding machines which may be easily and readily applied thereto having adjustable cutting tools which latter may be kept in the proper cutting contact with the grinding wheel of such machines 15 whereby the various grinding surfaces of the wheel may be constantly kept in condition for properly grinding the worm gears.

A further object of the invention is to provide 20 a setting head or attachment of the aforesaid character comprising a rocking cradle, which enables the inclination of the cutting tool for the setting of the bevelled face of the grinding wheel to be varied without modifying the location of the point of the tool when this latter is brought to 25 its starting position.

Another feature of the invention consists of a carriage mounted on the above-mentioned cradle and is comprised of a detachable guide-piece or gauge, which acts on the tool, mounted on the 30 said carriage, for the grinding of the bevelled face, in order to give to this face the profile of the gauge.

Still another feature of the invention consists 35 in that the head is movable on the framework of the machine, so that it can be adjusted to the various diameters of grinding wheels employed and that it can be used at the same time as a support for the guards for the protection of the operators.

40 Finally, the invention embraces the characteristics and the details of the means which are clearly set out in the following description and in the accompanying drawings. In these drawings:

45 Figure 1 is a perspective view of the setting head constructed in accordance with the invention applied to a worm gear grinding machine.

Figure 2 is a side view of the setting head as 50 applied to a grinding machine, but showing the grinding wheel thereof in section.

Figure 3 is a detailed front view of a portion of the grinding wheel and a vertical transverse section through the setting head or attachment for the grinding machine.

55 The mechanism or setting head is formed by a carriage 1 provided with grooves, which slides on the guide-rails 2 mounted on the grinding machine 3 (Figures 1 and 2).

The holding carriage 1 can therefore, owing to 60 the said guide-rails, move vertically along an axis

which is perpendicular to the shaft 4 of the grinding wheel, by reason of a rack 2a which is integral with the guide-rails and a toothed pinion 2b controlled by a wheel 5.

On the shaft 4 there is mounted a plate 6a, 5 which has an annular recess in which there is arranged a grinding wheel 6 formed of abrasive-matter.

The wheel 6 is intended for the grinding of worms 7, which are held in the machine by means 10 of suitable adjustable members. For this reason the said wheel 6 has a profile comprising an inner face 6b, a side face 6c and a bevelled face 6d having an appropriate curvature for grinding one of the flanks of the threads of the screw 15 7 without the faces 6c and 6d entering into contact with the flank of the adjacent screw.

The holding carriage 1, the height of which is varied according to the diameter of the grinding wheel 6, is constructed so as to have a semi- 20 cylindrical cage 1a at its upper part.

On this semi-cylindrical cage 1a a cradle 8, the base of which is also semi-cylindrical, can slide.

This sliding movement is guided by a grooved 25 rail 9 (Figure 3) and by a flat rail 10. The cradle 8 is held in the selected position on the carriage 1, by means of locking bolts 11 passing through the grooves 12 arranged in the cradle.

The movements of the cradle 8 relatively to the 30 carriage 1 are marked by means of a graduated arc 13 fixed on one of the members and a vernier 14 fixed on the other.

In the cradle 8 and parallel to the shaft 4 of the grinding wheel there are provided two dove- 35 tail-shaped guide rails 15, between which there slides a carriage 16.

This carriage has mounted on it a housing 17 which is arranged perpendicular relative to the 40 said carriage.

Inside this housing 17 there can slide with little friction a piston 18, the upper end 18a of which is provided with a thread. On this end there is screwed a milled nut 19 which abuts against a hollow nut 20, which screws to a greater 45 or less extent into the housing 17 so as to tighten or slacken, as may be desired, a spring 21 acting on the top of the piston 18.

Journalled within this piston 18 is a spindle 22 having projecting ends 24 which extend 50 through vertically elongated slots 25 and 26 formed within the housing 17. Carried by one of the projecting ends of this spindle is a roller 23.

The piston 18 is displaced vertically in the housing 17 under the force of the roller 23 guided 55 by the sinuosity of the cam 27. This vertical displacement of said piston 18 is guided by the projecting end 24 moving in the elongated slots 26 of the housing 17.

As it is necessary for the grinding of worms 60

that the grinding wheel 6 is annular in shape and of large diameter and that it has a profile comprising a cylindrical internal part 6b, a flat front part 6c and an external part of a particular shape 6d, the gauge 27 has the shape of this part 6d which alone does effective work and which requires resetting in accordance with the extent to which it is used.

For this purpose the piston 18 is provided with 10 a clamping chuck 28, which receives a diamond-holder 29. The diamond 30 must be able to come into contact with the part 6d in order to re-set it.

Consequently the part 6c also must always be re-set to an extent which depends upon the 15 treatment of the part 6d by the diamond 30. For this purpose, there is provided on the side of the cradle an internal boss 31 in which there slides a small piston 32 carrying a diamond-holding tool 33.

20 A spring 34 tends constantly to lift the piston 32 and to withdraw the diamond 35 from all contact with the grinding wheel 6.

The top of the piston 32 is fitted with a ball and socket joint-box 36, in which there is fitted 25 the end of a ball and socket lever 37.

30 The lever 37 rocks about a spindle 38 and has a handle 39, which can be grasped outside the machine. The spindle 38 is mounted in the cradle and it is therefore possible, by actuating the lever 37, to cause the lever 32 to descend when required and, in consequence, the diamond 35.

The movements of the carriage 16 on the cradle 8 are obtained by means of a lever 40, which is pivoted about a pin 41 which is integral with the 35 cradle and acts in the same way as the lever 37 on a ball and socket joint-box arranged in the carriage 16 and not shown in the drawings.

35 The gauge 27 is mounted in a small carriage 42 by means of fixing screws 43. The carriage 42 runs on a rail 44 provided on the cradle 8. It 40 is held stationary on this latter by means of a locking screw 45, the head of which runs in a T-shaped groove 46 provided in the cradle.

The movements of the carriage 42 relatively 45 to the cradle are ascertained on a graduated arc 47 and a scale 48 arranged on the two pieces.

It will thus be seen that it is easy, owing to the 50 circular movement of the cradle 8 and to the tangential movement of the carriage 16 relatively to the said cradle, to move the two diamonds 30 and 35 in such a way that their points come into coincidence, in the position for starting work, at the intersection of two perpendicular planes a—a and b—b (Figs. 2 and 3), which cut 55 one another at the angle formed by the parts 6c and 6d of the grinding wheel.

From this starting position, by actuating the levers 37 and 40 the diamonds can be moved against the grinding wheel 6.

60 The diamond 35 will move vertically so as to effect the re-setting of the flat part 6c of the grinding wheel.

The diamond 30 will move over the part 6d of the grinding wheel in accordance with the curvature 65 of the gauge 27 on which the roller 23 of the diamond-holding piston 18 moves when the carriage 16 moves over the cradle 8.

70 With this device it is possible to insure a constant rational shape and diameter of the grinding wheel 6 which enable a correct grinding of the worms to be carried out owing to the working of the part 6d of the grinding wheel against a single side of the screw thread.

The carriage 1 is provided with fins 49 on which

there may slide protecting aprons 50 fixed on the said wings by means of screws 51 passing through the grooves 52 arranged in the aprons.

Finally the cradle 8 is provided in front with a protecting screen 52. 5

The complete head of the machine therefore serves at the same time for the re-setting of the grinding wheel and as a protecting means for the workers against accidents which might be caused by chippings at the time of the said re-setting. 10

What I claim is:

1. The combination with a worm gear grinding machine having included therein a grinding wheel having a desired profile, means for keeping said profile comprising cutting tools, means carrying and guiding one of said cutting tools, means mounted on said machine on which said carrying means slides along an arc of a circle having as its center the intersection of the plane of the front face of said wheel profile and the plane of the external bevelled face of said wheel profile and means holding and guiding the other of said tools for the resurfacing of the side face of said wheel profile. 20

2. The combination with a worm gear grinding machine comprising a wheel having an annular groove formed in one face thereof, abrasive member mounted within said groove having grinding faces which at times require resetting, of an adjustable support, a cradle adjustably mounted 30 upon said support, cutting tools for resetting the several grinding faces of said abrasive member, a manually operable member for moving one of said tools into and out of cutting position with respect to one of the grinding faces of said abrasive member, a carriage slidably mounted upon said cradle, a vertically movable piston carrying the other of said cutting tools and adjustably mounted within said carriage, a gauge adjustably mounted upon said cradle for controlling the vertical movement of said piston, and a lever adjustably mounted upon said cradle whereby said carriage may be manually moved. 40

3. The combination with a worm gear grinding machine having included therein a rotatable 45 wheel carrying an annular abrasive member for grinding the gears, of means for resetting the grinding surfaces of said abrasive member comprising a cradle arranged above said wheel, means for adjustably supporting said cradle whereby 50 it may oscillate over said wheel, a carriage slidably mounted upon said cradle, a piston vertically movable within said carriage, a gauge adjustably mounted upon said cradle, guide rollers projecting from said piston and adapted to ride 55 upon said gauge, a cutting tool carried by said piston, and a manually operable lever connected to said carriage.

4. An attachment for worm gear grinding machines comprising a support, an arcuate guide 60 carried by said support, a cradle adjustably mounted upon said guide, said cradle having laterally arranged grooves therein, a carriage slidably mounted within the grooves of said cradle, a piston vertically movable within said carriage, 65 a cutting tool carried by said piston, manually operable means for controlling the vertical movement of said piston, a gauge adjustably mounted upon said cradle, means carried by said piston and adapted to ride upon said gauge, and a 70 manually operable lever connected to said carriage.

GABRIEL LECHESNE.
